UNITED STATES PATENT OFFICE

122,717

DESIGN FOR A DENTIST'S CABINET OR THE LIKE

John W. Christensen, Two Rivers, Wis., assignor to Hamilton Manufacturing Company, Two Rivers, Wis., a corporation of Wisconsin

Application February 19, 1940, Serial No. 90,357

Term of patent 7 years

To all whom it may concern:

Be it known that I, John W. Christensen, a citizen of the United States, residing in Two Rivers, Manitowoc County, Wisconsin, have invented a new, original, and ornamental design for a Dentist's Cabinet or the like, of which the following is a specification, reference being had to the accompanying drawing, forming a part thereof.

The figure is a perspective view of a dentist's cabinet or the like showing my new design, the other side of the cabinet (not shown) being like that which is shown. The back of the cabinet is plain.

I claim:

The ornamental design for a dentist's cabinet or the like, substantially as shown and described.
JOHN W. CHRISTENSEN.
